UNITED STATES PATENT OFFICE

CECIL VAN WYCK AND RALPH C. HYDE, OF LOS ANGELES, CALIFORNIA, ASSIGNORS TO CLAUDE NEON ELECTRICAL PRODUCTS CORPORATION, LTD., OF WILMINGTON, DELAWARE, A CORPORATION OF DELAWARE

ILLUMINATED SIGN

Application filed January 5, 1931. Serial No. 506,623.

Our invention relates to illuminated signs and has particular reference to signs illuminated by means of gaseous discharge tubes. In sign construction it has been the practice to provide a casing having a front wall upon which suitable sign indicia is placed, an illuminating device being placed within the casing so as to send its rays of light through the sign indicia.

10 We have discovered that such sign construction may be illuminated by means of tubular lamps located within the casing and that by arranging a reflector in the manner hereinafter described, a very pleasing appearance is given the sign, this appearance being particularly characterized by the fact that the sign appears to be illuminated by a multiplicity of sources of light considerably in excess of the number of light sources 20 actually used.

It is an object of our invention to provide a sign construction which may be illuminated with gaseous discharge lamps or other tubular lamps.

25 Another object of our invention is to provide a sign construction in which a small number of tubular lamps will illuminate the sign to present the appearance of the sign being illuminated by a much greater number of lamps.

Another object of our invention is to provide a sign construction in which the source of illumination comprises one or more gaseous discharge tubes and in which connecting 35 contact devices for supplying current to the lamps are used as a support for the lamps.

Other objects and advantages will be apparent from the following specification read in connection with the accompanying drawings in which

Figure 1 is a front elevational view of a sign constructed in accordance with our invention.

Fig. 2 is a vertical sectional view of our sign construction taken along the line II—II of Fig. 1; and

Fig. 3 is a vertical sectional view of our sign construction, taken along the line III—III of Fig. 2.

50 Referring to the drawings, we have illu-

strated a sign construction comprising a casing 1 having a rear wall 2, a front wall 3, and continuous side walls 4 connecting the front and rear wall to provide a completely enclosed housing for illuminating means and the sign indicia, as will hereinafter be described. The front wall 3 of the casing 1 is preferably constituted of some transparent or translucent material, such as glass and similar material.

Immediately beyond the front wall 3, we have illustrated an opaque masking device 5 which may be constructed of any suitable material to obscure certain portions of the front wall 3 to prevent light from passing through the front wall except at such portions or points as will define the sign indicia to be exhibited by the sign. For example, the embodiment of our invention herein illustrated shows the word "Fire" as cut out or left blank in the opaque mask 5 which is immediately beyond the front wall 3 so that light from the interior of the casing may pass outwardly only through such portions of the front wall as are not obscured by the mask.

Immediately behind the front wall 3, we have illustrated a reflector 6, this reflector being preferably formed of a plurality of groups of reflecting surfaces, each group comprising a pair of flat reflecting surfaces 7 and 8 arranged longitudinally within the casing 1 and arranged at an angle to each other so that the inner edges 9 of both surfaces 7 and 8 are joined to constitute an angled reflector of substantially V-shaped cross section. It will be noted that the reflecting surfaces 7 and 8 are not only angled with reference to each other but are preferably angled with reference to the front wall 3. That is, the outermost edges of the reflecting surfaces 7 and 8 are arranged close to the front wall 3 while the meeting inner edges 9 are spaced at a considerable distance from the front wall 3.

The means for illuminating our sign construction is illustrated as comprising a plurality of tubular lamps 10 either of the incandescent type or of the discharge type which may be made with a relatively small

- diameter, one of which is provided for each of the groups of reflector surfaces 7 and 8, the lamps being positioned parallel to the longitudinal axis of the reflecting surfaces 7 and 8 which constitute the associated reflector group. The lamp or tube 10 is preferably spaced inwardly of the juncture of the reflecting surfaces 7 and 8, the preferred location being just slightly to the rear of a center line represented by the dotted line 11, illustrated in Figure 2.
- With the lamps or tubes 10 located in this position, the appearance of that part of the sign illuminated by any one of the tubes 10 will show a plurality of distinctive bands of light, one of which bands represents the direct transmission of light from the lamp 10 through the front wall 3 of the casing, while the remaining bands of light are constituted by a plurality of reflections of the tube 10 from the reflecting surfaces 7 and 8. Such multiplicity of bands of light will produce the appearance indicated in the shaded lines 12 of Fig. 1, the white spaces between the shaded lines representing the appearance of the band of light, while the shaded portion represents a section of the sign indicia which is illuminated to a much less intensity.
- Referring, particularly, to Figures 2 and 3, it will be observed that a pair of mounting plates 13 and 14 are illustrated as being secured as by means of screws 15 to the rear wall 2 of the casing 1. These mounting plates are preferably formed of insulating material and have attached to the front faces thereof a plurality of spring clips 16 which constitute both supporting holders for the tubes or lamps 10 and the means for conducting electric current to the terminals of the tubes. The clips 16, illustrated in Fig. 2, are shown as extending a considerable distance in advance of the mounting plate 14, the contacting portion 17 of the clips being formed with a suitable curvature to conform with the size and shape of the contact terminals of the lamps, which will be engaged thereby. Thus the location of the lamps 10 relative to the reflector 6 may be prefixed by predetermining the length of the clips 16.
- With this arrangement of clips 16, the incandescent or gaseous tubes 10 may be readily inserted in the sign or removed therefrom and by interconnecting the clips 16, as by means of conductors 18, a number of straight tubes or lamps 10 may be employed to form a continuous lamp of any desired length depending upon the number of units 10 which may be employed in the sign.
- We have illustrated at 19 and 20 a pair of terminal conductors which may be connected to any suitable source of electric current for furnishing power to the lamps 10.
- With the construction illustrated and described herein, any suitable sign indicia may

be formed upon the front wall 3 of the casing 1 and a selected number of groups of reflecting surfaces 7 and 8 may be provided to the rear thereof. By arranging merely one lamp or tube 10 for each group of reflecting surfaces, the appearance of the finished sign, when illuminated, is that of a sign illuminated by a great number of bands of light.

While we have illustrated and described the preferred embodiment of our invention, we do not desire to be limited to any of the details shown or described herein, except as defined in the appended claims.

We claim:

1. In an illuminated sign, a casing, a translucent front wall for said casing, a reflector behind said front wall comprising a plurality of flat reflectors forming a plurality of adjacent groups of two reflectors each, the two reflectors of each group being arranged in V-shaped cross section relative to each other with the open side of the V directed toward said front wall, and the contiguous reflectors of each two adjacent groups forming a V-shaped cross section relative to each other with the open side of the V directed away from said front wall, and a tubular lamp disposed between the reflector forming each of said groups and parallel with the adjacent edges of the reflectors forming each group.

2. In an illuminated sign, a casing, a translucent front wall for said casing, a reflector behind said front wall comprising a plurality of flat reflectors forming a plurality of adjacent groups of two reflectors each, the two reflectors of each group being arranged in V-shaped cross section relative to each other with the open side of the V directed toward said front wall, and the contiguous reflectors of each two adjacent groups forming a V-shaped cross section relative to each other with the open side of the V directed away from said front wall, a tubular lamp disposed between the reflector forming each of said groups and parallel with the adjacent edges of the reflectors forming each group and spaced further from the open side of the V formed by reflectors of the associated group than from the point of the said V.

Signed at Los Angeles, California, this 30th day of December, 1930.

CECIL VAN WYCK.
RALPH C. HYDE.
